UNITED STATES PATENT OFFICE.

JOHN A. HALL, OF BAYSIDE, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 17, 1920. Serial No. 374,587.

To all whom it may concern:

Be it known that I, JOHN ALDEN HALL, a citizen of the United States, residing at Bayside, in the county of Queens, State of New York, have invented certain new and useful Improvements in Telephone-Exchange Systems, of which the following is a full, clear, concise, and exact description.

This invention relates to telephone systems and particularly to means for automatically connecting a calling line to an idle trunk.

The object of the invention is to provide a simple and efficient means, free from mechanical contrivances for preselecting and allotting idle trunks leading from a non-numerical switching apparatus of the type known as the cross bar switch.

In accordance with this object, a starting circuit is provided which will be made effective by the usual line relays associated with the calling lines. The actuation of a line relay will change the condition of the starting circuit so as to cause the movement of the 25 trunk bar associated with the first idle trunk. This movement will result in the closing of a return starting circuit which, through the control exercised over it by the line relay, will cause the energization of the line bar associated with the calling line. The movement of the line bar causes the engagement of the actuated trunk and line bars, whereupon the line is extended to the idle trunk, the idle trunk is marked as busy and 30 the trunk bar is released, now being held only by the continued actuation of the line bar. The line bar magnet acts as a cutoff relay to disconnect the line relay from the line and the trunk bar magnet together with 35 an auxiliary relay act to extend the starting wire to the next idle trunk.

The drawing is a diagrammatical representation of a means for carrying out the present invention.

1 and 2 represent so-called line bars. Each of these has a plurality of sets of multiple contact members 3 to which the tip, ring and sleeve conductors of the telephone lines are connected. The line bar 1 is associated with 45 a substation 4 and the line bar 2 is associated with a substation 5. Bar 1 is rotatably mounted in the frame of the switch by means of pivots 6 and 7 and it is normally moved toward the right by means of a coiled

spring 8 wound around the pivot 6. The 55 magnet 9 controls the armature 10 which, when attracted, pushes upon the end of the pivot 8 and moves the line bar toward the left. A cam arrangement 11 cooperating with a pin 12 causes the bar to rotate in a 60 counter-clockwise direction against the pressure of a spring 13. Thus, the multiple contact members 3 are moved downward.

In a very similar manner, trunk bars 14, 15 and 16 are pivotally mounted in the frame 65 of the apparatus. Each trunk bar carries a plurality of sets of multiple contact members 17 which are connected to trunk lines such as 18. By means of a lever arm 19, the trunk bar 15 may be rotated by the movement of an armature 20 of a trunk bar magnet 21.

Such a cross-bar switch operates in the following manner: First, the trunk bar 15 is rotated in a clockwise direction. Thereupon, 75 the line bar is rotated in a counter-clockwise direction until the multiple contact members 3 come into engagement with the multiple contact members 17. The trunk bar is then released and the contact members 17 which have made engagement with one set of contact members 3 are stressed into the position as indicated in the set shown directly above the trunk bar magnet 22. The remaining sets of multiple contact members 80 17, individual to trunk bar 15 resume their normal position where they will not be engaged by any other multiple sets of contact members 3.

The manner in which the arrangement 90 shown operates is as follows: It will be assumed that substation 5 has initiated a call and is connected through the line bar 2 and the trunk bar 15 to a trunk connected to conductors 23. In this case, as will be hereinafter more fully pointed out, a relay 24 associated with the trunk bar magnet 21 will be in its energized condition. If now 95 the substation 4 initiates a call, a circuit will be completed from battery, the right-hand winding of relay 25, contact springs 26, through the loop at the substation 4, contact spring 27, the left-hand winding of relay 25 to ground. Relay 25 attracts its armature and, in so doing, places a 100 ground through its outer left-hand armature on conductor 28. Conductor 28 extends 105 this ground through the contacts 29 and

30, the right-hand armature and alternate contact of relay 24, the contacts 31 and 40 controlled by the trunk bar magnet 22, the right hand armature and back contact of relay 33, the winding of trunk bar magnet 22, the winding of relay 33 to battery and ground. Both magnet 22 and relay 33 are energized in this circuit. Magnet 22, through its armature, rotates the trunk bar 10 14 and relay 33 quickly pulls up its left-hand armature, and slowly pulls its right-hand armature due to the influence of a spring 34. The energizing circuit for magnet 22 is now transferred from spring 40 15 to spring 32 and thence directly to the winding of magnet 22 so that it is now independent of the right hand armature of relay 33. Magnet 22 also closes a circuit from ground, contact spring 35, contact spring 20 36, conductor 37, the contact and inner left-hand armature of relay 25, the right-hand windings of line bar magnet 9 to battery and ground. Magnet 9 is energized and attracts both its right-hand and left-hand 25 armatures. Under the influence of its armature 10, line bar magnet 1 is actuated whereupon the contact members 3 and 17, shown in the upper left-hand corner of the figure come into engagement. It should be noted 30 at this point, that the windings of magnet 9 are so designed that the energization of the right-hand windings will cause the attraction of both the right-hand and left-hand armatures and that the subsequent 35 energization of the left-hand windings will hold both of these armatures attracted. If, however, the left-hand windings are energized first, only the left-hand armature will be attracted since it does not work against 40 as heavy a spring as the right-hand armature.

The telephone line from substation 4 is now extended through the contact members 3 and 17 to the trunk 18 whereupon the loop 45 at the substation closes a circuit for the energization of relay 38. Relay 38 attracts its armature and closes a circuit for the energization of slow-releasing relay 39 which, in turn, through its right-hand armature, 50 places a ground on the third conductor of trunk 18. This ground extends now through the contact and left-hand armature of relay 33, the winding of relay 33 to battery and ground. At the same time, it 55 shunts the winding of magnet 22 so that relay 33 remains energized and magnet 22 becomes deenergized. The ground placed on the third conductor of trunk 18 is also extended through conductor 41 to the left-hand windings of magnet 9 to battery and ground, whereby the magnet 9 is held in its actuated position. Through its left-hand armature, magnet 9 actuates the contacts 60 26 and 27 to cut off the relay 25 from the line of substation 4. Thereupon the ground 65

is removed from the conductor 28 and the right-hand windings of magnet 9 are opened.

All of this operation has taken the smallest fraction of a second and it will be assumed that shortly after, the right-hand armature of relay 33 moves to its attracted position, whereupon the conductor 28 is extended through the contacts 29 and 30, the right-hand armature of relay 24, contacts 31 and 40, the right-hand armature and contact of relay 33 and thence to the winding of the next in turn trunk bar magnet.

It should be noted that as soon as the trunk bar magnet 22 becomes energized and 80 before the right-hand armature of relay 33 moves to its attracted position, the starting conductor 28 is extended to the winding of magnet 22 through the contacts 31 and 40, the right-hand armature and back contact of relay 33, the winding of magnet 22 in place of the circuit heretofore described.

Since further extension of the call over the trunk 18 forms no part of the present invention, it will not be further described. 90 Upon the termination of the conversation, the subscriber at substation 4 replaces his receiver on its hook and thereby deenergizes relay 38 resulting in the removal of ground from the third conductor whereby relay 33 95 and magnet 9 are deenergized and retract their armatures and the apparatus returns to its normal position.

On a call incoming to the substation 4, the third conductor 41 is grounded in a well-known manner and the line bar magnet 9 attracts only its left-hand armature to cut off the relay 25 from the influence of the line.

What is claimed is:

1. In a switching mechanism, line bars each comprising a movable structure carrying a plurality of sets of multiple contact members, trunk bars each comprising a movable structure carrying a plurality of sets 110 of multiple contact members, said line bars and said trunk bars being constructed and arranged to cooperate whereby connections may be extended from any line bar to any trunk bar, magnets for operating said line 115 bars, magnets for operating said trunk bars, a line relay associated with each line bar magnet, an auxiliary relay associated with each trunk bar magnet, a circuit controlled by said line relays normally extending through the first of said trunk bar magnets, and means controlled by said auxiliary relay associated with said trunk bar magnet for extending said circuit to the next trunk bar magnet. 125

2. A plurality of magnets, an auxiliary relay associated with each of said magnets, a second plurality of magnets, an auxiliary relay associated with each of said second magnets, a circuit controlled by said first 130

- 5 relays extending to the first in order of said second magnets, means controlled by said auxiliary relay associated with said first in order of said second magnets for extending said circuit to a second in order of said second magnets, a circuit controlled by said second magnets and said first relays for controlling said first magnets, and means jointly controlled by said first and said second magnets for controlling said first magnets.
- 10 3. A plurality of magnets, a relay associated with each of said magnets, a second plurality of magnets, a relay associated with each of said second magnets, a circuit controlled by said first relays extending to a first in order of said second magnets, means controlled by said relay associated with said first in order of said second magnets for extending said circuit to a second in order of said second magnets, a circuit controlled by said second magnets and said first relays for controlling said first magnets for controlling both said circuits.
- 15 4. A magnet, a relay associated with said magnet, a second magnet, a relay associated with said second magnet, a circuit controlled by said first relay for controlling said second magnet, a circuit controlled by said sec-

ond magnet and said first relay for controlling said first magnet, means jointly controlled by said first and second magnets for controlling said second relay, and means controlled by said second relay for further controlling said first circuit. 35

5. In a telephone system, a cross bar switch comprising a plurality of line bar magnets, an auxiliary relay associated with each of said magnets, a plurality of trunk bar magnets, an auxiliary relay associated with each of said trunk bar magnets, a circuit directly controlled by said first auxiliary relays for controlling the first in order of said trunk 40 bar magnets, and means controlled by the first in order of said second auxiliary relays for extending control of said circuit to the next in order of said trunk bar magnets. 45

6. In a telephone system, a cross bar switch comprising a plurality of line bar magnets, an auxiliary relay associated with each of said magnets, a plurality of trunk bar magnets, a circuit controlled by said auxiliary relays for controlling said trunk bar magnets, and a circuit controlled by said trunk bar magnets for controlling said line bar magnets. 55

In witness whereof, I hereunto subscribe my name this 16th day of April, A. D. 1920.

JOHN A. HALL.
